UNITED STATES PATENT OFFICE.

FANE H. COSNER, OF COOPEN, WEST VIRGINIA.

SIGN-HOLDER.

1,209,560.

Specification of Letters Patent. Patented Dec. 19, 1916.

Application filed April 11, 1916. Serial No. 90,450.

To all whom it may concern:

Be it known that I, FANE H. COSNER, a citizen of the United States, residing at Coopen, in the county of Braxton and State of West Virginia, have invented new and useful Improvements in Sign-Holders, of which the following is a specification.

This invention relates to sign holders, the object of the invention being to provide a device of this character for holding municipal or other signs, whereby signs of different kinds and sizes may be interchangeably separated and displayed and secured to a building, sign post or other support with a minimum of injury to said support.

A further object of the invention is to provide a sign which is simple of construction, capable of being manufactured and sold at a comparatively low cost, which will hold the sign spaced from the support, and which will securely clamp signs of different sizes.

The invention consists of the features of construction, combination and arrangement of parts herein fully described and claimed, reference being had to the accompanying drawing in which:—

Figure 1 is a front elevation of the improved sign holder. Fig. 2 is a side elevation of the same. Fig. 3 is a vertical longitudinal section.

In carrying my invention into practice, I provide a bracket member 1, comprising a comparatively long and narrow plate having a substantially flat body portion 2, which body portion is provided with terminal apertured ears 3 for the passage of fastenings to secure the bracket to a wall or other support, and offset portions 4 connecting said ears with the bracket body. It will be observed that these offset portions dispose the body portion 2 of the bracket so as to stand out from the wall or other support, allowing the sign to be applied and removed with facility, while at the same time spacing the sign from the wall or other support to reduce liability of injury to the latter to the minimum.

The bracket body 2 is provided with a longitudinally extending slot 5, and mounted upon the said bracket body, at right angles thereto in parallel relation to each other, are holding bars or strips 6 and 7 having longitudinally grooved or channeled inner faces 8, which grooves or channels are designed to receive and hold the longitudinal edges of the sign proper 9.

It will, of course, be understood that the parts of the holder may be made of any desired size, and, as shown, one of the bars, as the bar 6, is provided with a lug 10 for the passage of a rivet or other fastening 11, which also passes through one end of the body 2 and rigidly fastens the bar 6 in position. The other bar 7 is also provided with an apertured lug 12 for the passage of a bolt 13, and this bolt 13 extends through the slot 5 and is slid able in said slot, whereby the bar 7 is adjustable toward and from the bar 6 so as to properly dispose said bars for holding signs of different widths. The bolt 13 is provided with a wing nut 14 for clamping the adjustable bar in adjusted position at any point along the length of the slot 5.

It will thus be seen that the holder may be secured to a suitable support and that it is adapted to detachably hold metal or other signs of different sizes to display the same in an effective manner, as well as to permit of the removal of the signs and substitution of others as desired. Furthermore, it will be seen that the device provides for the display of signs without injuring or defacing a wall or other support, other than is necessary for the passage of the fastenings which secure the bracket in place. The device is thus adapted especially for displaying signs upon municipal and other buildings, etc., or wherever it is desired to display signs without injuring or defacing the building or support to any appreciable extent.

I claim:—

A sign holding device comprising a vertically disposed bracket bar having end attaching portions, said bar also having a longitudinally extending slot and short imperforate portions between the ends of said slot and said attaching portions, a lower channeled holding bar extending transversely of said bracket bar and provided with a medial ear, said bar and ear being arranged to bear against the lower imperforate portion of the bracket bar, fastening means passing through said ear and said imperforate portion of the bracket bar and rigidly securing said channeled bar in position, an upper channeled holding bar extending transversely across the slotted portion of the bracket bar and parallel with the first-named channeled bar and also provided with a medial ear, the channeled faces of said bars being arranged opposite each other and the inner walls of the channels thereof

being disposed to lie in contact with the bracket bar, a bolt passing through the ear of the upper channeled bar and slidably engaging the slot in the bracket plate, whereby
5 the upper channeled bar is adjustable substantially the full length of the body of the bracket bar toward and from the lower

channeled bar, a clamping nut engaging said bolt, and clamping members upon the outer walls of the channels of the channeled bars 10 for clamping the edges of a sign plate against the inner walls of said channels.

In testimony whereof I affix my signature.
FANE H. COSNER.
